United States Patent Office.

JACOB LEMLEY, JR., OF NEWTOWN, VIRGINIA, ASSIGNOR TO HIMSELF,
I. W. YEAKELL, AND C. O. KLINE, OF SAME PLACE.

Letters Patent No. 71,520, dated November 26, 1867.

IMPROVEMENT IN MEANS FOR MEASURING AND LAYING OUT GARMENTS.

The Schedule referred to in these Letters Patent and making part of the same.

TO ALL WHOM IT MAY CONCERN:

Be it known that I, JACOB LEMLEY, Jr., of Newtown, county of Frederick, and State of Virginia, have invented certain new and useful Improvements in Graduated Rule for Cutting Garments; and I do hereby declare that the following is a full, clear, and exact description of the same, reference being had to the annexed drawings, and to the letters of reference marked thereon, and made a part of this specification, in which—

Figure 1 is a full view of the breast-plate of the former.

Figure 2 is a full view of the back and shoulder-plate of the former.

Figure 3 represents five of the series of graduated scales used by me.

These drawings are all drawn on a half scale.

The nature of my invention consists in combining with a stationary former or rule, on which are indicated all the angles necessary for cutting the garment as well as a guide-table of distances, a series of graduated scales which are entirely independent of the former, but are so arranged that they can be readily attached thereto and detached therefrom, thus enabling me to cut on a single former, whose angles and distances are arranged for a person of the smallest size, a garment suited to and that will fit a person of the largest proportions.

To enable others skilled in the art to make and use my invention, I will proceed to describe its construction and operation.

A is a former for the breast-plate, and is so arranged that all the angles and distances necessary to be indicated in marking out the material for the breast and under-arm cut are fully shown. B is a former similar in design to A, but intended for the back. Both A and B are formers which are arranged, as to distances and in all other respects, to suit a person measuring twenty-seven inches around the chest. When a larger garment is to be cut, I apply one of the series of graduated scales, as shown in red in figs. 1 and 2. C is the centre of the under-arm cut. D D are a series of graduated scales, extending from 27 to 47, only five of the series being shown, but which are twenty-one in number. The figures and distances that are spaced off on these scales are the result of actual measurement. a a show the different points or angles which it is necessary to mark on the material in order properly to cut out the desired pattern. b b are a series of lines, which all radiate from the centre C of the arm-hole. On these lines are various numbers, which are of no importance when the garment is intended for a person of twenty-seven inches around the breast, for the different angles are obtained simply by placing the former on the material and dotting down the distances at the various points a a. But when the garment is intended for a person measuring over twenty-seven inches, so that one of the series of graduated scales has to be used, the numbers on the lines b b become indispensably necessary, as will be hereafter fully described.

The operation, when one of the series D of the graduated scales is used, is as follows: The series as used by me is composed of twenty-one strips suitably spaced and marked. These strips are numbered 27, 28, and so on up to 47. Suppose the person for whom the coat is intended measures twenty-nine inches around the chest, then the scale marked 29 is used in connection with the former, as shown in red in fig. 2. If he measures forty-seven inches, then the scale marked 47 is used, as shown in red in fig. 1.

To illustrate the principle, let us take the scale-strip D marked 47, and apply it to the former, which is done by passing a pin or needle, e, through the edge of the strip, and also through the opening in the centre of the arm-hole C, and thence to the table or board on which the material rests. It will be observed that the pin or needle acts as a pivot, and furnishes a centre bearing for the strip D. When this scale-strip D is applied to the first line b we find the figure 3; this figure shows the distance from the centre of the first angle required. Instead of making the mark at a, we run along the scale until we come to the figure 3, and there make the mark, which would be at about the point d. We then revolve the scale until we come to the next line b, which is marked 6 $\frac{1}{2}$. Instead of marking at a, we run along the scale until we reach 6 $\frac{1}{2}$, and there make the mark, as shown at e, and so on until we have all the distances properly ascertained and suitably marked. The former B is shown with the scale-strip D which is marked 30 applied. The principle by which it is operated is precisely similar to that before illustrated.

The only thing required to be done in order to cut a garment of any desired size is to ascertain the number of inches the person measures around the chest, then take the scale-strip D which is marked with the same number and apply it to the former, as shown, and then revolve the strip, stopping at each line b, marking the different angles on the material in the manner described.

By my plan I am enabled to cut the arm-hole, which is usually the most difficult point, with perfect accuracy and great facility. Find the figure 3 on the scale, commence at the point f, and draw a curved line, stopping at f', which it will be observed by reference to fig. 1 is a little more than a semicircle, then make a straight cut from f', which is the front of the arm, to the point marked f'', which is the lower shoulder-point, and the entire work of cutting the arm-hole is accomplished.

The great advantage of this invention consists in its extreme simplicity. The series of graduated scale-strips being entirely free and independent of the former, if care is taken in selecting the one whose number is the same as the inches the person measures around the chest, it is impossible for a mistake to occur, there being nothing to confuse the operator, as is the case when all the tables of distances and angles are spread out on the sheet which contains the pattern-plate.

Having thus fully described my invention, what I claim therein as new, and for which I desire Letters Patent, is—

The combination of the formers, on which are indicated a single table of measurements, with a series of graduated scales, said scales being entirely independent of each other and of the former, but so arranged as to be susceptible of being readily attached to and detached from the former, substantially as described.

In testimony whereof I have signed my name to this specification in the presence of two subscribing witnesses.

JACOB LEMLEY, JR.
